Application November 6, 1930, Serial No. 493,807
In Germany July 20, 1929

4 Claims. (Cl. 202—99)

The present invention relates to improvements in low temperature carbonization apparatus.

A process and apparatus for carrying out low-temperature carbonization of bituminous carbonaceous materials has already been proposed according to which the hot gases or vapors, which may be inert or may contain oxygen, are blown through the layer of fuel to be treated at a temperature suitable for the low-temperature carbonization and in such amount that the layer of fuel is brought into vigorous motion on its bed, but to avoid combustion or gasification of the carbonized fuel to a higher extent than is necessary to produce the heat for carbonization.

We have now found that this process may be carried out in a specially advantageous manner with inert gases in a retort provided with several grates one above the other, the grates being permeable for gases but not to any substantial degree for the carbonaceous material to be carbonized. The carbonaceous material is supplied to the uppermost grate and passes from one grate to the other through at least one aperture in each grate provided with closing means, such

as sluices intermittently opened, or with bucket wheels conveying the material from one grate to the next without allowing substantial amounts of gases to pass. The said apertures are arranged in the grates at opposite ends thereof to compel the carbonaceous material to pass over the grates in a zigzag course and are preferably provided with tubes or hoppers extending to a height above the grate corresponding to that of the desired thickness of the layer of carbonaceous material upon the grate, so that only the uppermost layer of carbonaceous material can pass through the said apertures. The said tubes or hoppers are preferably arranged adjustable in length. The inert gases are passed into the retort from below through the series of grates and layers of carbonaceous material thereon at such a speed that each individual layer is set in vigorous motion.

The nature of this invention will be further described with reference to the accompanying drawing which in Figs. 1 and 2 shows in vertical cross-section arrangements of apparatus in accordance with the present invention. Referring to Figure 1 in detail *a* denotes a low-temperature carbonization retort containing four grates, *b*, *c*, *d* and *e*, arranged one above the other. The fuel to be subjected to low-temperature carbonization, such as for example brown coal and soft coal rich in bitumen, passes from a hopper *l* through a worm conveyer *k* onto the upper

grate *b*. The fuel passes from one grate to another through tubes *n* (extending upward from the grates into the space between two grates) combined with conduits *q* extending downward from the grates and provided with bucket wheels *h* and is finally removed through an outlet *m* and a worm conveyer *i* after it has been subjected to low-temperature carbonization. A burner *f* serves to prepare the inert gases of combustion. The burner is provided with tubes *p* and *o* for the admission of fuel gas and air or like oxidizing gases. The inert gases of combustion pass through the single grates, each laden with fuel, and are withdrawn at *g* together with the vapors from the low-temperature carbonization. It is preferable to leave a free space above each layer of carbonaceous material so that not too much dust is carried along.

Furthermore, it is preferable to construct the grates with as great a length as possible so that the fuel has to traverse a long path while passing through the retort. In this manner a better exchange of heat between the gases and the fuel is effected.

In the said Figure 1 the regulation of the height of the layers of carbonaceous material on the single grates is effected by means of the rotary bucket wheels *h* and the tubes *n*, but this may be effected equally well by other means, as for example by means of sluice valves, or by automatic means. It is essential that the downward stream of carbonaceous material is so led in counter current to the ascending inert gases over the single grates that the fuel bed is in vigorous motion in each single stage.

With a retort constructed according to the present invention a substantially greater efficiency is obtained than with the systems hitherto known, and an excellent protective treatment of the vapors from the low-temperature carbonization and the best utilization of the heat supplied are also obtained.

We have further found that an apparatus constructed on the hereinbefore described principle is very suitable for carrying out other heat-treatments of bituminous carbonaceous materials as for example the gasification of solid fuels.

Thus, it is especially advantageous and simple to carry out the drying, degasification and gasification (for example low-temperature carbonization) in a shaft, for example rectangular or circular, so that the single processes are carried out separate from each other on the horizontal or slightly inclined superimposed grates which are permeable for gas but substantially impermeable

for the fuel, the hot gases flowing through the grates from the bottom to the top while the fuel flows in counter current to the gases over the single grates from the top to the bottom through 5 suitable opening devices. The fuel spreads itself out on the single grates in such a manner that there is a large gas space between the surface of the fuel and the grate lying next above it.

By working in this simple manner an accurate 10 control over the single independent processes of drying, degasification and gasification is obtained. In this manner it is possible to carry out each of the three processes independently under the most favorable conditions, as for example 15 of temperature, and still to retain the combination of the different processes in one shaft. The juxtaposition and confusion of the single processes, such as is possible for example in a shaft low temperature producer with or without low 20 temperature carbonization insertions or attachments by reasons of the formation of grooves or channels in the bed of fuel, is entirely avoided according to the present invention.

The fuel slides from one grate to the next for 25 example through sluices, rotary bucket wheels, mushroom valves and the like. When the cross-section of the grates is of large dimensions it is preferable to move the fuel on the single grates in order to produce beds having as uniform a 30 thickness as possible. This may be effected for example by blowing in the air for the gasification or the hot producer or scavenging gases which flow through the shaft upwards in such a quantity as to keep the fuel in active movement on its bed 35 or to whirl up and down, but to avoid combustion or gasification of the fuel to a higher extent than is necessary to produce the heat for carbonization.

Figure 2 of the accompanying drawings represents 40 a vertical section of an apparatus which is particularly suitable for carrying out the drying, degasification and gasification in one shaft, the single processes taking place separate from each other.

Referring to Figure 2 in detail S denotes a shaft 45 which is divided into several chambers by horizontal grates R₁, R₂, R₃ and R₄. The fuel, for example brown coal, is sluiced in in the usual manner from a receptacle Y by means of a 50 hopper X and bucket wheel Z and flows in a horizontal direction over the grate R₁. The fuel passes through a rotary bucket wheel F₁ onto the grate R₂ and from this through a rotary bucket wheel F₂ on to the grate R₃. Finally the fuel 55 passes through a rotary bucket wheel F₃ on to the gasifying grate R₄. The ash of the coal gasified on the grate R₄ is removed through a rotary bucket wheel F₄. The grates R₁ and R₂ act as 60 drying zones. On the grate R₃ the coal passes through the low temperature carbonization zone while the grate R₄ constitutes the bottom of a lignite coke producer which may be operated with 65 any desired temperature by means of a gasifying agent such as air, carbon dioxide, steam or mixtures of these gases blown in at L. It is blown in with such a force that the gases flowing through the shaft S keep the fuel in motion on the single grates. In this manner the thickness 70 of the fuel bed on the single grates is kept uniform and a movement from the inlet end to the outlet end takes place. The gases leave at G. Further advantages of the process according to 75 the present invention consist for example in that irregular distribution of temperature, the forma-

tion of channels and slagging are avoided in all cases.

The grates must offer a free passage to the ascending current of gas but on the other hand must prevent the fuel passing from one grate to the one below it except through the sluices. It has been found to be especially suitable to construct these grates by arranging fire clay plates in a thickness equal to that of building bricks one beside another with their edges so that a small slit of from about 0.5 to 3 millimetres remains free. These grates do not allow even finely grained material to fall through while they only offer a slight resistance to the gases which is necessary for a uniform distribution of the gases. If the fuel is completely gasified or burned on the lowermost grate, this may have any suitable shape which ensures the removal of the ash, as for example movable grates, grates with scraping devices and the like.

The process may be used with special advantage for example for brown coal which has been wholly or partly predried. When the material has been predried to a large extent, lignite coke may be withdrawn at F₄ instead of ash by only 80 burning as much coal on the grate R₄ as is necessary for the preheating and low temperature carbonization on the remaining grates.

It is also possible, to influence the working 85 conditions on the single superimposed grates from outside besides the combustion or gasification on the lowest grate, by leading in air, carbon dioxide and the like at any suitable place, for example above one or more of the lower grates 90 of fuel, through admission pipes C.

When employing steam or gases containing 95 steam as the gasifying agent it is preferable to employ the steam in a highly superheated condition in order that the gasification may be continuous. Working in this manner renders it possible to obtain a final gas rich in hydrogen which is suitable for many purposes and moreover the sensible heat of that part of the steam which is not converted by the gasification is utilized in an 100 advantageous manner for the low temperature carbonization.

What we claim is:

1. An apparatus for distilling and gasifying coal comprising a retort, a plurality of superimposed grates at spaced intervals within said 105 retort, each of said grates covering the entire horizontal cross-sectional area of said retort and being permeable to gases and adapted to support the coal to be distilled, at least one conduit for said coal in each grate, the said conduits in 110 the several grates being out of vertical alignment, closing means within said conduits, means for feeding said coal onto the uppermost grate, means for discharging the coke from the lowermost grate, a conduit for leading gas into the bottom 115 of said retort, and a conduit for drawing off gas at the top of said retort.

2. An apparatus for distilling and gasifying coal comprising a retort, a plurality of superimposed grates at spaced intervals within said 120 retort, each of said grates covering the entire horizontal cross-sectional area of said retort and being permeable to gases and adapted to support the coal to be distilled, at least one conduit for said coal in each grate, the said conduits in 125 the several grates being out of vertical alignment, closing means within said conduits, means for feeding said coal onto the uppermost grate, means for discharging the coke from the lowermost 130 grate, a conduit for leading gas into the bottom 135 of said retort, and a conduit for drawing off gas at the top of said retort.

3. An apparatus for distilling and gasifying coal comprising a retort, a plurality of superimposed grates at spaced intervals within said 140 retort, each of said grates covering the entire horizontal cross-sectional area of said retort and being permeable to gases and adapted to support the coal to be distilled, at least one conduit for said coal in each grate, the said conduits in 145 the several grates being out of vertical alignment, closing means within said conduits, means for feeding said coal onto the uppermost grate, means for discharging the coke from the lowermost 150 grate, a conduit for leading gas into the bottom

- of said retort, a conduit for drawing off gas at the top of said retort, and a conduit for introducing gas above at least one of the lower grates.
3. An apparatus for distilling and gasifying coal comprising a retort, a plurality of superimposed grates at spaced intervals within said retort, each of said grates covering the entire horizontal cross-sectional area of said retort and being permeable to gases and adapted to support the coal to be distilled, at least one conduit for said coal in each grate, the said conduits in the several grates being out of vertical alignment and each conduit extending to some predetermined distance into the space between two grates, closing means within said conduits, means for feeding said coal onto the uppermost grate, means for discharging the coke from the lowermost grate, a conduit for leading gas into the bottom of said retort, and a conduit for drawing off gas at the top of said retort.
4. An apparatus for distilling and gasifying the coal to be distilled, at least one conduit for said coal in each grate, the conduits in adjacent grates being at diametrically opposite sides of said retort, closing means within said conduits, means for feeding said coal onto the uppermost grate, means for discharging the coke from the lowermost grate, a conduit for leading gas into the bottom of said retort, and a conduit for drawing off gas at the top of said retort.
